WALTER E. BELCHER, OF WINNIPEG, MANITOBA, CANADA

ELECTRIC IRON

Application filed August 10, 1929. Serial No. 384,901.

The invention relates to improvements in electric irons and an object of the invention is to provide a latch or trigger associated with the handle of the iron and which can be conveniently gripped by the hand gripping the handle and when gripped will operate through a suitable switch provided and embodied as part of the iron equipment to maintain the circuit containing the iron heating element closed and which is arranged further that upon the finger pressure being released from the latch during the ironing operation, the latch will move under spring pressure and the movement so occasioned will actuate the switch to stop the flow of current to the heating element of the iron.

A further object of the invention is to provide an iron embodying a switch controlling the circuit containing the iron heating element and wherein the circuit is automatically broken through the switch upon the heat of the heating iron reaching a predetermined temperature.

A further object of the invention is to provide an iron which can be heated to several temperatures but wherein the electric circuit leading to the element is automatically broken when each selected temperature is reached and the iron will not continue to heat further unless the operator actuates a latch provided for the purpose.

A further object of the invention is to provide a heating iron wherein the normal gripping movement of the fingers of the hand in gripping the iron handle is used to actuate a spring pressed latch and such movement of the latch operates a switch to close the circuit leading to the heating element of the iron and wherein also, gravity actuated locking means is provided for automatically locking the latch with the switch closed and upon the iron being brought to an up ended position with the butt thereof down and to associate also with the iron a thermostat operated by the heat of the iron and adapted to release the locking means upon the heat of the iron reaching a predetermined temperature, such resulting in the breaking of the electric circuit through the switch under the pressure of the latch spring.

With the above more important and other minor objects in view which will become more apparent as the description proceeds, the invention consists essentially in the arrangement and construction of parts hereinafter more particularly described, reference being had to the accompanying drawings, in which:

Fig. 1 is a view of the iron, the base being shown for the greater part in side elevation and the upper part thereof in vertical longitudinal section.

Fig. 2 is a longitudinal sectional view centrally through the iron, certain parts being shown in side elevation and the iron appearing in rested or not in used position.

Fig. 3 is a perspective view showing the thermal strip used.

Fig. 4 is a plan view showing the interior construction of the plug used.

Fig. 5 is an enlarged detailed vertical sectional view through a portion of the plug and showing the type of toggle switch used.

Fig. 6 is an enlarged detailed vertical sectional view at 6-6' Figure 4.

Fig. 7 is a perspective view showing the support for the switch.

Figs. 8 and 9 are perspective views of the members forming the toggle switch.

Fig. 10 is an enlarged detailed vertical sectional view at 10-10' Figure 3.

In the drawings like characters of reference indicate corresponding parts in the several figures.

The body of the iron comprises the base or sole 1, an overlying electrical heating element indicated generally by the reference numeral 2 and a metal block 3 thereabove, the block being fastened to the base by suitably located screws 4 which also serve to hold the element in place. A casing 5 encloses the block and bears on the upper face of the sole being fastened by screws 6 screwing into the block 3.

The rear end of the iron is provided with the customary pair of contacts, one of which is indicated in dotted outline at 7, these contacts being carried by the casing 5 and suitably insulated therefrom and being connected electrically within the casing as indicated 100

at 8 with the opposite ends of the heating element. To the rear end of the casing a plug receiving socket 9 is also attached by bolts 10, the socket taking a slightly inclined upstanding position and containing the contacts 7. The socket is extended to provide two rests or legs 11 and 12 which are adapted when the iron is turned to the position shown in Figure 2 to support the iron in its not in use or resting position.

10 All the above parts of the iron are of well known and ordinary construction and accordingly I have not considered it necessary to herein give a more detailed description of the same.

15 same.

16 The iron handle 13 is provided at the under side with a longitudinally extending channel or groove 14 and it is supported in its position above the body of the iron by a bar 15 fastened to the casing by the screws 6 and having the ends thereof up turned as shown and secured by screws 16 to the ends of the handle. The up turned rear end of the bar 15 is provided with a vertical slot 17 and the up turned front end of the bar is provided with a slot 18. A pivot pin 19 crosses the rear end of the channel 14 being carried by the handle and the pin supports pivotally a finger latch or trigger 20 which has the rear end 21 provided with a substantially V-shaped notch 22 and the forward end provided at the lower corner with a right angled notch 23, it being observed that the rear end of the latch protrudes freely through the slot 17 and that the forward end thereof terminates within the up turned forward end of the bar 15.

40 turned forward end of the bar 10. A spring 23 is interposed between the latch and the handle which spring operates to continuously press the forward end of the latch downwardly. The socket 9 receives a contact plug indicated generally by the reference numeral 24, the plug having the lower end thereof fastened permanently within the socket by a bolt 25 provided and having feed wires 26 and 27 leading from the upper end and communicating with a suitable source of electric current, as is usual. The plug contains similar electrical spring contacts 28 and 29 of well known type adapted, 45 in the inserted position of the plug as shown, to make electrical connection with the contacts 7 hereinbefore mentioned and the plug embodies in its construction a toggle switch 50 indicated generally by the reference numeral 30 which controls the passage of current to the heating element of the iron.

The details of the switch will be shortly described but I might at this time mention that it embodies as part of its structure a pivoted trip bar 31 projecting from the plug and entering the notch 21 of the iron, the arrangement being such that when the latch 20 is in the position shown in Figure 2, the toggle switch is in the on position and current is flowing to the heating element of the

iron and such that when the latch is permitted to swing to the position shown in Figure 1, the trip bar 31 is actuated by the latch to turn the toggle switch so that it is in an off position and there is no current flowing to the heating element of the iron. Accordingly, the position of the latch controls the "on" or "off" condition of the iron. 70

"on" or "off" condition of the switch. A lever 32 is pivotally supported by a pin 33 from the bar 15 and this lever is curved to approximate the curvature of the forward end of the bar and has the upper end thereof terminating in a weight or ball 34 and provided also with a horizontally disposed locking pin 35 and the lower end extending through a longitudinally extending slot 36 provided in the casing 5 and terminating in a plurality of down turned spaced fingers 37, 38 and 39 which overlie the upper face of the block 3. A thermostat 40 in the form of a curved semicircular shaped strip is secured by a screw 41 to the block 3, the thermostat lying in the horizontal plane and having the free end thereof crossing the block in a location considerably in advance of the pin and positioned such that it will be caught by one or other of the fingers in a manner later described. The strip is formed from two pieces of metal having different co-efficients of expansion and contraction and it is closely associated with the block so that it will expand and contract under the varying temperature of the block, the free end of the thermostat drawing closer to the pin 41 as the temperature increases and passing further away from the pin as the temperature diminishes.

The pin 35 passes freely through the slot 18 and any suitable means can be employed for preventing the withdrawal of the pin from the slot under the gravitational influence of the weight 34. Such is herein shown as a tit 35' on the inner end of the pin adapted to engage with the lower end of the slot 18. Obviously the same object could be accomplished by dispensing with the tit and limiting the down swinging of the upper end of the lever 32 by contact of the lower end thereof with the under side of the bar 15. 105 110 115

thereof with the under side of the handle. 115
When the heating element of the iron is not heated, the controlling toggle switch is in the position shown in Figure 1 and at such time the front end of the latch is down and the locking lever is free, that is to say, it is held in the out position or in a direction away from the handle by the gravitational action of the ball and at such time, the fingers are all above the plane containing the upper edge of the thermostat. 120
125

When one desires the iron to become heated, he grasps the handle in the usual way and naturally grips the latch and at the same time, he can swing the iron to the position shown in Figure 2 where it is resting on the legs. The gripping of the handle and the

latch causes the forward end of the latch to move towards the handle into the position shown in Figure 2 and in such position it becomes automatically locked by the pin 35 which is at such time forced in by the gravitational action of the weight which at such time is acting to swing the upper end of the lever towards the handle. The movement of the latch to the position shown in Figure 2 is sufficient to cause the closing of the toggle switch and the consequent flow of current to the heating element. Accordingly the iron will commence to heat the instant it is brought to the up ended position as shown in Figure 2 and simultaneously the latch is automatically locked by the pin so that one can then release his hand grip and leave the iron to heat.

The movement occurring in the lever under the influence of the weight when the iron is brought to the up ended position is sufficient also to swing the fingers towards the block 3 and into a position normally to the inner side of but clear of the outer end of the thermostat or strip 40. The distance which the outer end of the thermostat is at this time from the front finger 37 is utilized as a timing element determining when the latch will will be unlocked and the toggle switch thrown to open position.

Obviously as the iron heats in the position shown in Figure 2, the free end of the thermostat will gradually move towards the anchored end thereof and I desire it to contact with the finger 37 approximately about the time that the iron is heated a sufficient temperature for ordinary ironing purposes which will be approximately around 350° F. After contacting with the first finger 37, the further movement of the free end of the thermostat due to the gradually increasing temperature of the iron will swing the lower end of the lever away from the block and coincident with the time that the first finger is escaping over the upper edge of the thermostat, the pin 35 is withdrawing from the notch 22 and releasing the latch to swing down under the action of the spring 23. The instant the latch is released, it actuates the toggle switch and turns off the current supply to the heating element. Accordingly if unattended, the element is in the above manner protected by the thermostat against being overheated which latter operates entirely automatically to actuate the switch and at a time when a predetermined or selected temperature is reached.

If one desires to iron after the iron has become heated and the latch released he can do so without fear of burning or scorching the clothes as the current will remain off until the latch is raised. Should one desire at any time while ironing to heat the iron, all he has to do is to grip the latch to cause it to rise and this will manipulate the switch and

turn on the current and the current will only remain on as long as the latch is gripped so that the operator has complete control of the heating of the iron during the ironing operation. I might here remark that while ironing is being done, the ball operates to hold the pin 35 clear of the adjoining end of the latch and the fingers clear of the thermostat.

By providing several fingers, I am able to have several heat ranges when the iron is heating in the position shown in Figure 2 and this is explained in the following way. Assuming that the latch has been released by the engagement of the thermostat with the first finger 37 in the manner already explained, one can, if he desires, pull the latch again towards the handle at which time, it will be automatically locked by the pin 35 and the free end of the thermostat will then be between the first and second fingers 37 and 38. The latch will remain locked with the current on until the thermostat, due to the increasing temperature of the iron, engages and shifts the second finger an amount to withdraw the pin 35 and release the latch. This can be gauged to occur when the temperature of the iron has reached say 450° F.

If this temperature is not sufficient for the particular ironing purpose of the operator, he can again move the latch towards the handle where it becomes locked automatically, the current is turned on and the free end of the thermostat is then between the fingers 38 and 39. When the thermostat has further contracted, due to increased temperature, to contact with the finger 39 and move it sufficiently far to withdraw the pin 35, the latch will be again released and the current turned off at which time the temperature may be approximately 600° F.

While I have described a plurality of fingers, of course it will be understood that the iron might be made with only one finger, as such might be found all that is necessary for practical purposes, the finger being actuated by the thermostat to unlock the latch and throw the switch to off position at the time the temperature of the iron has reached a predetermined temperature sufficient for all practical ironing purposes.

The structural details of the toggle switch within the plug are now described. Internally the plug contains two bars 43 and 44 which are connected to the entering ends of the feed wires 26 and 27 and the bar 43 makes direct electrical connection with the contact 29 while that 44 is connected electrically by a screw 45' to an angle plate 45. Directly opposite the angle plate 45, a further angle plate 46 is fastened by a screw 46' to the plug and between the free ends of the angle plates, I locate a pair of spaced substantially V-shaped spanner bars 47 and 48, the ends of which are carried by similar plates 49 and 50 fastened to the plug.

The spanner bars are supplied with out turned tongues 51 and 52 which have their outer ends passed through suitable openings provided in the angle plates 45 and 46 and these tongues form pivots for the ends of a yoke 53 which carries slidably a spindle 54 having a forked end 55. The forks 55 span a cross strip 31' provided at the inner end of the trip bar 31, the trip bar protruding outwardly through a suitable opening provided in the plug and having the sides thereof fitted with extending lugs 31^x which enter receiving openings 56 provided in the spanner bars 47 and 48. A spring 57 is passed around the spindle 54 and engages the yoke and the forks and normally presses the forks continuously towards the cross strip 31'. An insulating plate 58 is inserted in the plug, this overlying the bars 49 and 50 and being cut away centrally to receive the yoke.

20 cut away centrally to receive
When the protruding outer end of the trip
bar is pressed in one direction, the yoke which
is in direct electrical contact with the bar
44 swings back and strikes the insulating
strip 58 and when the trip bar is moved in
25 the other direction, the yoke swings over and
makes contact with the inturned end 59 of a
bar 60 which is in direct electrical connec-
tion with the contact 28.

30 The spring of course acts to make the toggle switch operate positively and quickly when the yoke is swung just past dead central position. As before stated, the trip bar is actuated by the adjacent end of the latch and 35 operates when the latch is down as shown in Figure 1 to break the flow of current to the heating element of the iron and when the latch is up, to close the circuit through the toggle switch and effect the heating of the heating element.

40 heating element. While I have entered into a detailed description of the particular type of switch employed, I wish it to be understood that any type of switch which can be operated by 45 the swinging end of the latch to make and break the circuit containing the element will serve my purpose.

What I claim as my invention is:

What I claim is as follows:

1. The combination with an electrically heated flat iron, of a normally open circuit controlling switch therefor, a spring pressed latch pivotally carried by the iron handle and having operating connections with the switch and arranged in the pressing of the latch towards the handle to close the switch and in the release of the latch to open the switch under the action of the latch spring, gravity operated means for locking the latch against movement in the closed position of the switch and upon the iron being swung into a resting position butt down and means controlled by the rising temperature of the iron for releasing the latter locking means upon a preselected temperature being reached.

2. The combination with an electrically heated flat iron, of a normally open circuit controlling switch therefor, a spring pressed latch pivotally carried by the iron handle and having operating connections with the switch and arranged in the pressing of the latch towards the handle to close the switch and in the release of the latch to open the switch under the action of the latch spring, gravity operated means for locking the latch against movement in the closed position of the switch and upon the iron being swung into a resting position butt down and a thermostat actuated by the heat of the iron and arranged to release the locking means aforesaid upon the heat of the iron reaching a predetermined temperature.

3. The combination with an electrically heated flat iron, of a member conveniently located, in respect to the iron handle to be grasped and moved towards the handle in the gripping of the handle, means holding said member normally in a position away from the handle, means closing the electrical heating circuit of the iron upon the member being pressed towards the handle, means automatically locking the latter member in its pressed position upon the iron being brought to an up ended rested position butt down and thermostatically operated means for releasing the locking means upon the heat of the iron reaching a predetermined temperature. 85 90 95

perature.

4. The combination with an electrically heated flat iron, of a switch carried by the iron and controlling the iron heating circuit, said switch being normally in an open position, a spring pressed latch pivotally carried by the iron handle and adapted to be pressed towards the handle against the action of the spring by the hand gripping the handle, operating connections between the latch and the switch arranged to close the switch in the pressing of the latch towards the handle and to open the switch under the pressure of the latch spring upon the release of the latch, means for automatically locking the latch against movement in its pressed position with the switch closed and upon the iron being swung to an up ended rested position butt down and means actuated by the rising temperature of the iron for releasing said locking means upon the heat of the iron reaching a predetermined temperature.

5. The combination with an electrically heated flat iron, of a switch carried by the iron and controlling the iron heating circuit, said switch being normally in an open position, a spring pressed latch pivotally carried by the iron handle and adapted to be pressed towards the handle against the action of the spring by the hand gripping the handle, operating connections between the latch and the switch arranged to close the switch in the pressing of the latch towards

the handle and to open the switch under the pressure of the latch spring upon the release of the latch, gravity operated means for locking the latch in its pressed position with the 5 switch closed upon the iron being turned to an up ended rested position butt down and a thermostat operating under the increasing temperature of the iron in such latter position to release said locking means upon the 10 heat of the iron reaching a predetermined temperature.

6. The combination with an electrically heated flat iron, of a switch carried by the iron and controlling the iron heating circuit, 15 said switch being normally in an open position, a spring pressed latch pivotally carried by the iron handle and adapted to be pressed towards the handle against the action of the spring by the hand gripping the handle, operating 20 connections between the latch and the switch arranged to close the switch in the pressing of the latch towards the handle and to open the switch under the pressure of the latch spring upon the release of the 25 latch, a weighted lever pivotally carried by the iron and provided with a locking pin and arranged in the swinging of the iron to a rested position, butt down, to effect, under the action of gravity, the locking of the latch 30 in its pressed position, by the pin and a thermostat associated with the iron and the lever and adapted upon the heat of the iron reaching a predetermined temperature to actuate the lever and withdraw the locking pin.

35 7. In an electrically heated flat iron, the combination with a spring pressed circuit controlling member arranged to be moved towards the iron handle in the gripping of the handle by the hand and to close through 40 such movement the heating circuit of the iron, of means operating automatically to lock the aforesaid member against movement in its hand pressed position upon the iron being brought to a rested up ended position 45 butt down and means actuated by the rising temperature of the iron for releasing said locking means upon the heat of the iron reaching a predetermined temperature.

8. In an electrically heated flat iron, the 50 combination with a spring pressed circuit controlling member arranged to be moved towards the iron handle in the gripping of the handle by the hand and to close through such movement the heating circuit of the 55 iron, of a gravity actuated lever pivotally carried by the iron and operating, upon the iron being brought to an up ended rested position butt down, to lock the member against movement in its hand pressed position and a thermostat associated with the iron 60 and the lever and adapted to move the lever and unlock the member upon the heat of the iron reaching a predetermined temperature.

Signed at Winnipeg this 6th day of June,
65 1929. WALTER E. BELCHER.
